UNITED STATES PATENT OFFICE.

BOYD M. JOHNSON, OF METUCHEN, NEW JERSEY, ASSIGNOR TO THE CARBORUNDUM COMPANY, OF NIAGARA FALLS, NEW YORK, A CORPORATION OF PENNSYLVANIA.

HEAT EXCHANGER.

Application filed February 9, 1924. Serial No. 691,576.

To all whom it may concern:

Be it known that I, BOYD M. JOHNSON, a citizen of the United States, residing at Metuchen, county of Middlesex, and State 5 of New Jersey, have invented a new and useful Improvement in Heat Exchangers, of which the following is a full, clear, and exact description.

This invention relates broadly to heat exchangers, and more particularly to heat exchangers of the type adapted for transferring heat from live gases of combustion to air or other fluids. The purpose of the present invention is to enable the use of the 10 high temperature silicon carbide radiating combustion chamber in a heat exchanger constructed mainly of materials having a comparatively low heat resistance. This purpose is accomplished by protecting the 15 metal sheets and tubes which constitute the main body of the heat exchanger from the direct radiation of heat from the walls of the combustion chamber by means of silicon carbide tubes interposed between the 20 metal tubes and the walls of the combustion chamber and a fire-clay wall forming a refractory lining for a portion of the 25 metal walls of the heat exchanger.

Since thin metal sections will transmit 30 heat more readily than heavy refractory materials, a very efficient heat exchanger is thus obtained by combining the possibilities for efficient combustion in the silicon carbide radiating combustion chamber with the high 35 heat conductivity of silicon carbide in the tubes next to the chamber and the higher heat conductivity of the metal tubes and sheets. This efficiency is obtained with a 40 comparatively low cost of construction due to the use of metal sheets and tubes throughout the main body of the heat exchanger.

A preferred embodiment of the invention is shown in the accompanying drawings, in which:—

45 Figure 1 is a sectional plan view of the heat exchanger, the section being taken on the line I—I of Figure 2;

50 Figure 2 is a longitudinal vertical section on the line II—II of Figure 3;

55 Figure 3 is a transverse vertical section on the line III—III of Figure 2;

60 Figure 4 is a detail view of the silicon carbide radiating combustion chamber, and

Figure 5 is a detail of cooperating refractory elements for supporting the silicon 55 carbide tubes.

In the illustrated embodiment of the invention, the heat exchanger comprises an outer shell 2 formed of spaced metal walls having some suitable heat insulating material 3 filling the space therebetween. An off-take 4 for the heated air communicates with the space within this outer shell through a side thereof, while an in-take 5 for the cold air communicates with such space 60 through an opening in a metal plate 6 which forms the closure for the rear end of the shell.

Within the outer shell 2 is an inner metal shell 7, the top, side and end walls of which are spaced from the top, side and end walls of the outer shell. The lower portion of the inner shell is protected by an inner fire-clay wall 8 forming a refractory lining for such lower portion and enclosing a space 70 within which is placed a silicon carbide radiating combustion chamber 9. This chamber is of U-shape and communicates at one end with the exterior of the heat exchanger through an opening 10 in the front end portion of the fire-clay wall 8. It will be noted by reference to Figure 2, that the front end portion of the fire-clay wall 8 extends through openings in the front end walls of the inner and outer shells and bridges the 75 space between such front end walls. The opening 10 forms the burner opening for the combustion chamber, this chamber being provided at the other end of its U-shaped 80 passage with an outlet opening 11 through 85 which the gases of combustion pass from the combustion chamber into the inner shell. The combustion chamber is spaced from the floor of the heater by a suitable fire-clay base 12 which is provided with spaces 13 to 90 permit the circulation of the gases of combustion between the base and the lower wall of the combustion chamber.

95 Directly above the top wall of the combustion chamber is arranged a row of silicon carbide tubes 14, and another row of silicon carbide tubes 15 is arranged opposite the rear end wall of the combustion chamber. These silicon carbide tubes 14 and 15 are 100 supported at their ends in the side portions of the fire-clay wall 8 and in the side 105

walls of the inner shell 7, said fire-clay wall being composed, in part, of bricks 16 of the form shown in Figure 5. These bricks have cooperating recesses therein forming 5 circular openings for receiving the ends of the tubes. Above the silicon carbide tubes 14 are placed banks of metal tubes 17, supported at their ends in the side walls of the inner metal shell 7 and communicating with 10 the spaces between these side walls and the side walls of the outer shell. Another row of metal tubes 18 is interposed between the silicon carbide tubes 15 and the rear end portion of the fire-clay wall 8, these tubes 15 being supported in the side portions of said wall and in the side walls of the inner shell in the same manner as the tubes 14 and 15. Within the inner shell are horizontal metal baffles 19 which compel the gases of combustion, after they emerge from the opening 11, to make several passes the full length 15 of the inner shell before passing out of the heat exchanger through the off-take flue 20. This flue is located at the rear end of the 20 heat exchanger while the outlet 11 from the combustion chamber is located at the front end of the heat exchanger. The flue 20 has the same width as the inner shell and is located in the space between the rear end wall 6 of the outer shell and the rear end wall 21 of the inner shell and spaced from both of these walls. The rear end wall 21 and the 25 top wall of the inner shell extend beyond the side walls of the latter to the side walls 30 of the outer shell, so that the air entering through the intake 5 is compelled to travel upwardly to the space between the top wall of the inner shell and the top wall of the outer shell, then to travel to the front end of 35 the heater into the space between the front end wall of the inner shell and the front end wall of the outer shell. Baffles 22 between the side walls of the inner shell and the side walls of the outer shell are so arranged that 40 the air, after entering the space between the front end wall of the inner shell and the front end wall of the outer shell, is compelled to make several passes the width of the inner shell through the tubes 14, 15, 17 45 and 18 before it can finally pass out of the heat exchanger through the off-take 4.

The walls of the inner shell and the baffles 19 which direct the flow of the gases of combustion through the inner shell will, 50 preferably, be constructed of calorized metal plates built up in sections and bolted with calorized bolts. The tubes 18 and the tubes 17 in the lower banks may also be made of calorized metal since they are subjected to 55 higher temperatures than the tubes 17 in the upper banks. The tubes 17 in the upper banks may be made of ordinary iron or steel. If the heat exchanger is to be operated at very high temperatures, all of the 60 metal tubes may be made of calorized metal,

whereas, if the heat exchanger is to be operated at relatively low temperatures, all of the metal tubes may be made of ordinary iron or steel.

It will be apparent that the heat is supplied to the heat exchanger both in the form of radiant heat from the silicon carbide radiating combustion chamber and also by the sensible heat in the gases of combustion emerging from the combustion chamber. 70 These gases, as they emerge from the combustion chamber, are directed by the baffles 19 so that they are compelled to make several passes the length of the inner shell before passing to the stack through the off-take flue 20. In their travel through the inner shell in this manner they are in contact with the banks of tubes which carry the air to be heated. After making the last pass through the inner shell they then pass through the off-take flue 20 which is surrounded by the air entering the heat exchanger through the intake 5. The air to be heated passes around the off-take flue 20, over the top of the inner shell, down through 80 the space between the front end wall of the inner shell and the front end wall of the outer shell and then makes several passes the width of the inner shell through the tubes which are surrounded by the hot gases 85 of combustion. The air in its travel through the heat exchanger may pass through any of the tubes of the bank composing each pass. The silicon carbide, steel and/or calorized metal tubes of the bank composing 90 each pass all discharge into a common chamber, that is, the chamber 23 or the chamber 24 (Figure 1). Upon such discharge, due to natural convection currents, the air which has been heated the most in the lower and hotter tubes changes position with the relatively cooler air which has passed through the upper tubes. This means that on the next pass cooler air enters the hot tubes than would be 95 the case if all the tubes of the bank composing a pass did not discharge into a common chamber. The same thing occurs in each successive pass, the general temperature of the air being raised but no local hot spots developing. Air is continually in motion in the spaces between the inner and outer walls of the heat exchanger, which 100 prevents excessive temperatures in and excessive loss from the outer walls. This cooling effect of the air also obviates the necessity of high temperature resisting refractories in the major portion of the heat exchanger. 115

The advantages of the invention arise 120 from the arrangement of a silicon carbide radiating combustion chamber in combination with metal conducting tubes and interposed conducting tubes of silicon carbide and a protecting fire-clay wall, whereby it is possible to utilize to the maximum extent the 125 130

energy derived from the combustion of the fuel in a heat exchanger which may be constructed at a comparatively low cost. The silicon carbide tubes not only protect the metal tubes from the direct radiation of heat from the walls of the combustion chamber, but they also further protect the metal tubes by absorbing a portion of the heat contained in the gases of combustion before these gases 10 come in contact with the metal tubes. The arrangement whereby the silicon carbide, steel and/or calorized metal tubes of the bank composing each pass discharge into a common chamber is particularly adaptable 15 for a heat exchanger from which a large volume of air at a comparatively low temperature is desired, and enables a high temperature heating medium to be employed without overheating any portion of the heat 20 exchanger. Since the effective temperature on any of the tubes is the average of the surrounding gas temperature and the inner air temperature, the lower tubes would be continually at a much higher average temperature 25 than results with the arrangement of the present invention were the mixing chamber at the end of each pass omitted.

While I have shown and described a preferred embodiment of the invention, it will 30 be understood that changes may be made in the details of construction shown without departing from the spirit of the invention or scope of the appended claims. It will also be understood that the invention is not limited 35 in its use to heating air.

I claim:

1. A heat exchanger, comprising a radiating combustion chamber, metal heat transfer means arranged adjacent said chamber, independent refractory heat transfer means interposed between said combustion chamber and said metal heat transfer means as a baffle to partially protect the metal heat transfer means from direct radiation of heat 40 from said combustion chamber, and means for conducting the medium to be heated through said exchanger in contact with one surface of said metal and refractory heat transfer means, substantially as described.
2. A heat exchanger, comprising a radiating combustion chamber, metal heat transfer means arranged adjacent said chamber, independent refractory heat transfer means interposed between said combustion chamber 45 and said metal heat transfer means as a baffle to partially protect the metal heat transfer means from direct radiation of heat from said combustion chamber, all of said heat transfer means being adapted to be heated also by direct contact of the gases of combustion therewith, and means for conducting the medium to be heated through said exchanger in contact with one surface of 50 said metal and refractory heat transfer means, substantially as described.

3. A heat exchanger, comprising a radiating combustion chamber, a plurality of metal conducting tubes arranged adjacent said chamber, and a plurality of independent refractory conducting tubes interposed between said combustion chamber and said metal tubes as a baffle to partially protect the latter from direct radiation of heat from 55 said combustion chamber, substantially as described.

4. A heat exchanger, comprising a metal shell, a plurality of metal conducting tubes supported in said shell, a radiating combustion chamber within said shell having a silicon carbide radiating wall, and a plurality of independent silicon carbide conducting tubes interposed between said wall and said metal tubes as a baffle to partially protect the latter from direct radiation of heat from 60 said wall, all of said tubes being adapted to be heated also by direct contact of the gases of combustion therewith, substantially as described.

5. A heat exchanger, comprising a metal shell, a plurality of metal conducting tubes supported in said shell, a combustion chamber within said shell adapted to heat said tubes by direct contact of the gases of combustion therewith and having a silicon carbide radiating wall, a refractory wall interposed between said chamber and a portion of said shell, a plurality of silicon carbide conducting tubes interposed between said radiating wall and said metal tubes and supported by said refractory wall, and means for conducting the medium to be heated through all of said tubes, substantially as described.

6. A heat exchanger, comprising an inner metal shell, an outer metal shell surrounding and spaced from said inner shell and having an inlet and an outlet for the medium to be heated, a plurality of metal tubes supported in said inner shell and communicating with the spaces between the inner and outer shells, a combustion chamber within said inner shell adapted to heat said tubes by direct contact of the gases of combustion therewith and having a silicon carbide radiating wall, and a plurality of silicon carbide conducting tubes interposed between said wall and said metal tubes and communicating with the spaces between the inner and outer shells, substantially as described.

7. A heat exchanger, comprising metal heat transfer means, at least a portion of which is constructed of calorized metal, a radiating combustion chamber having a silicon carbide radiating wall, independent silicon carbide heat transfer means interposed between said wall and said metal heat transfer means as a baffle to partially protect the latter from direct radiation of heat from said wall, and means for conducting the medium to be heated through said exchanger

- 1 in contact with one surface of said metal and silicon carbide heat transfer means, substantially as described.
- 5 8. A heat exchanger, comprising metal conducting tubes and silicon carbide conducting tubes, the silicon carbide tubes being separate from the metal tubes, means for directing hot gases through said exchanger in contact with one surface of said tubes in 10 such manner that the silicon carbide tubes absorb a portion of the heat contained in such gases before they come into contact with the metal tubes, and means for directing the medium to be heated through said 15 exchanger in contact with the opposite surface of said tubes, substantially as described.
9. A heat exchanger having a passage therethrough for hot gases of combustion, metal conducting tubes and silicon carbide 20 conducting tubes arranged in said passage, the silicon carbide tubes being separate from the metal tubes and arranged to absorb a portion of the heat contained in the gases before they reach the metal tubes, and means 25 for conducting the medium to be heated through said tubes, substantially as described.
10. A heat exchanger, comprising outer metal walls, inner metal walls spaced from 30 said outer walls, independent metal and silicon carbide conducting tubes supported in said inner walls and communicating with the spaces between the inner and outer metal walls, means for directing the medium to be heated through the tubes and the spaces between the inner and outer walls, and means 35 for directing hot gases of combustion through the heat exchanger first in contact with the silicon carbide tubes and then in contact with the metal tubes, substantially 40 as described.
11. A heat exchanger, comprising an inner metal shell, an outer metal shell having 45 its walls spaced from the walls of the inner shell, metal and silicon carbide conducting tubes supported by the inner shell and communicating with the spaces between the inner and outer shells, a combustion chamber 50 within the inner shell and adapted to heat said tubes by direct contact of the gases of combustion therewith and having a silicon carbide radiating wall, the silicon carbide tubes being arranged between said radiating wall and the metal tubes, a metal off-take 55 flue leading from said inner shell, and an intake flue for the medium to be heated completely surrounding said off-take flue and leading to the spaces between the inner and outer shells.
12. A heat exchanger, comprising a plurality of banks of conducting tubes each composed in part of silicon carbide and in part of independent metal tubes, a mixing chamber between the discharge ends of the tubes of each bank and the intake ends of the tubes of the next bank, and means for directing hot gases through said heat exchanger to heat such tubes, the construction and arrangement being such that the silicon carbide tubes are subjected to higher temperatures than the metal tubes, substantially 65 as described.
13. A heat exchanger, comprising a plurality of banks of conducting tubes arranged side by side and each composed in part of silicon carbide and in part of independent metal tubes, baffle means for compelling the medium to be heated to make a pass through the tubes of one bank in one direction and then through the tubes of the next bank in 70 the opposite direction, a mixing chamber between the discharge ends of the tubes of each bank and the intake ends of the tubes of the next bank, and means for directing hot gases through said heat exchanger to heat such tubes, the construction and arrangement being such that the silicon carbide tubes are subjected to higher temperatures than the metal tubes.
14. A heat exchanger, comprising a radiating combustion chamber having a silicon carbide radiating wall, a plurality of banks of conducting tubes arranged side by side above said wall and each composed of metal tubes and independent silicon carbide 75 tubes arranged between said wall and the metal tubes, means for directing the gases of combustion in contact with said tubes in such manner as to subject the silicon carbide tubes of each bank to the higher temperatures, and a mixing chamber between the discharge ends of the tubes of each bank and the intake ends of the tubes of the next bank.

In testimony whereof I have hereunto set my hand.

BOYD M. JOHNSON.
